US00D904330S

(12) **United States Design Patent** (10) Patent No.: **US D904,330 S**
(45) Date of Patent: **** Dec. 8, 2020**

(54) **MOBILE PHONE**

(71) Applicant: **LG ELECTRONICS INC.**, Seoul (KR)

(72) Inventors: **Jiyoun Cha**, Seoul (KR); **Hyonl Kim**, Seoul (KR); **Hyunggon Ryu**, Seoul (KR); **Byeongwook Kim**, Seoul (KR); **Seungbeom Park**, Seoul (KR)

(73) Assignee: **LG Electronics Inc.**, Seoul (KR)

(**) Term: **15 Years**

(21) Appl. No.: **35/507,683**

(22) Filed: **May 2, 2019**

(80) **Hague Agreement Data**

Int. Filing Date: **May 2, 2019**

Int. Reg. No.: **DM/203775**

Int. Reg. Date: **May 2, 2019**

Int. Reg. Pub. Date: **Nov. 8, 2019**

(30) **Foreign Application Priority Data**

Dec. 6, 2018 (KR) 30-2018-0057492

(51) LOC (12) Cl. **14-03**

(52) U.S. Cl.

USPC ..... **D14/138 G**; D14/248

(58) **Field of Classification Search**

USPC ..... D14/137, 138 C, 138 G, 138 R, 138 AC, D14/138 D, 248, 341

CPC . G06F 1/1626; H04M 1/0202; H04M 1/0235; H04M 1/0237; H04M 1/0239; H04M 1/0266; H04M 1/0268; H04M 1/027; H04M 1/0295
